UNITED STATES PATENT OFFICE.

GEORGE A. N. WOODCOCK, OF FLUSHING, NEW YORK, ASSIGNOR TO PETREE & DORR ENGINEERS, INC., OF NEW YORK, N. Y., A CORPORATION OF CUBA.

LIQUID-DELIVERY APPARATUS.

Application filed September 3, 1927. Serial No. 217,853.

The general object of the present invention is to provide improved means for delivering a liquid such as lime solution at a measured rate which may be readily varied 5 to suit different conditions of use. The invention was primarily devised and is especially adapted for use in adding lime to sugar juice in definite proportions for defecation purposes. More specifically, the 10 object of the invention is to provide apparatus for the purpose specified, characterized by its mechanical simplicity and reliability, and by the ease and accuracy with which the rate of lime delivery may be 15 maintained and varied as conditions may require.

The various features of novelty which characterize my invention are pointed out with particularity in the claims annexed to 20 and forming a part of this specification. For a better understanding of the invention, however, its advantages and specific objects obtained with its use, reference should be had to the accompanying drawings and descriptive matter, in which various forms of 25 the invention are illustrated and described.

Of the drawings:

Fig. 1 is an elevation, partly in section on line 1—1 of Fig. 2;

30 Fig. 2 is a plan view with parts broken away and in section;

Fig. 3 is an elevation in section on the line 3—3 of Fig. 1, and with parts broken away;

35 Fig. 4 is a partial section taken similarly to Fig. 1, and illustrating a modified construction;

Fig. 5 is a partial section on line 5—5 of Fig. 4;

40 Fig. 6 is a partial section on line 6—6 of Fig. 4.

In the drawings, and referring first to the construction shown in Figs. 1, 2 and 3, A represents a tank serving as a receptacle for 45 the lime solution or other liquid to be supplied at a definite rate. Dipping into the liquid partially filling the tank A is a rotating member B carried by a horizontal shaft B¹ journalled in the tank structure and 50 rotated at a proper rate, as by means of a belt running over a drive pulley B³ mounted on the shaft B¹. When used to defecate sugar juice, the pulley B³ is advantageously belted to a drive pulley on the grinding mill 55 to insure the proper relative speeds of the

mill and member B. Advantageously, the tank A is formed as shown with a removable upper portion forming an enclosing hood for the member B.

The rotating member B comprises a disc 60 B² secured to a hub member fastened on the shaft B¹. Secured to the front side of the disc B adjacent its periphery, are buckets or measuring receptacles C¹, C², C³, etc. These buckets are each in the form of hollow cylinders, one end of which is bolted or otherwise secured to the disc B, and the other end C¹⁰ of which is formed with an opening at C¹¹ specially shaped for a purpose hereinafter described. A slot is formed in the 70 cylindrical wall of each bucket. Each bucket, as it passes through its uppermost position discharges its contents into the upper receiving end D' of an inclined chute or trough D. To insure that all of the 75 liquid so discharged will enter the upper end of the trough or chute D, and that none of it will run down the disc B, the side C¹² of the bucket slot over which the liquid discharges is advantageously formed with a 80 shoulder C¹³ adjacent the disc B which projects above the main portion of the side C¹² in the discharge position of the bucket.

The opening C¹¹ formed in the front end wall C¹⁰ of each bucket, is so shaped that 85 the amount of liquid held by the bucket will not depend on the height of liquid level in the tank, provided there is enough liquid in the tank to charge the bucket when the latter is at its lowermost position. To this 90 end the opening C¹¹ is formed with a circular portion so curved about the axis of the bucket that as each bucket moves from its lowermost position into its discharge position, the distance from the bottom of the 95 bucket to the level C¹⁴ at which overflow through the opening C¹¹ can occur, is constant. This feature is of special practical importance because of the fact that in the operation of such apparatus it is not practically feasible to maintain the lime solution or other liquid to be delivered at a constant 100 level in the tank A. With a fluctuating liquid level the buckets, if not formed with the special overflow openings C¹¹, would hold more liquid as they move above the liquid level in the tank A when that level is relatively high, than when it is relatively low.

As shown, the trough D is secured at its 110

ends to the tank structure, the upper end of the trough extending through the front wall of the hood portion A'. The trough D, which has a wide, flat bottom, is provided with means whereby a greater or lesser portion of the liquid discharged into the upper end of the trough by the buckets C¹, C², C³, etc. may be passed to each of two outlets E and F, and the balance returned to the tank. To this end vanes or deflector fingers G and g are adjustably mounted within the trough. These vanes divide the liquid coming down from the upper portion of the trough into three streams, one stream passing to the outlet E, one to the outlet F, and the third stream passing to an opening D⁵ through which the excess liquid is returned to the pool in the tank A.

As shown, the vane G is mounted on a shaft G¹ journaled in and extending transversely to the top and bottom walls of the trough. An arm G², secured to the shaft G¹ and carrying a set screw G³ which may be screwed into an engagement with the top wall of the trough, forms a means by which the vane G may be secured in any desired angular adjustment. The vane G co-operates with a stationary trough partition G⁴ at the lower side of the vane to form the corresponding wall of the channel leading to the outlet E. The vane g may be exactly like the vane G and is shown as having associated with its parts g¹, g², g³, and g⁴ corresponding to the parts G¹, G², G³ and G⁴, respectively. To facilitate the adjustment of the vanes G, the top wall of the trough D is provided with a hinged cover section D². A hinged cover section D³ is also provided to permit access to the outlets D, E and F.

To even the downflow of the stream of liquid and insure its proper distribution across the width of the trough D, a spreader plate H is located in the upper portion of the trough D and hinge connected at H' to the top wall of the trough. The lower edge of the plate H is held at a regulated distance above the bottom wall of the trough by a threaded pin secured to the plate and passing upward through a slot D⁴ in the top wall of the trough, and a nut H² threaded on said pin and engaging the trough top wall. A special advantage of the spreader plate arrangement described is that it may be lifted up for cleaning purposes without disturbing the adjustment of the nut H².

The apparatus shown in Figs. 1, 2 and 3 possess important practical advantages for its intended use. Its construction is simple and durable, and it is reliable and effective in operation. The measuring buckets can well be made out of galvanized sheet iron with the parts welded or riveted together so that the cost of bucket construction and renewal is relatively small. The capacity

of the apparatus may be varied through wide limits by changing the number of buckets carried by the disc B². Practically the only limits to the number of buckets to be used are those imposed by the size of the disc B which limits the maximum number of buckets which can be used, and the desirability of arranging the buckets so that the revolving member is properly balanced. With the described buckets there is no significant variation in the rate of delivery due to variations in spillage, or to the extent to which the buckets are filled with varying liquid levels in the tank A, such as have interfered with the effectiveness of apparatus of this general type heretofore employed.

The character of the construction is such as to minimize interference with operation by the inevitable incrustation when lime or like solutions are handled. By making the hood A' removable, and by providing the hinged trough sections D² and D³, the removal of incrusted lime and other cleaning operations can be readily carried out when necessary. The provisions of the adjustable flow dividing means, including the vanes G and g, in the trough D, permit of ready adjustments from time to time to compensate for changes in sugar juice composition or other conditions making it desirable to vary the relative proportions of sugar juice and lime added thereto. It will be understood that lime solution or lime and water may be supplied to the tank A in any usual or suitable manner, and that means for injecting air into the liquid in the tank A or for otherwise agitating the liquid may be provided as is usual, but as these features form no part of the present invention, I have not thought it necessary to illustrate and describe them in detail.

In Figs. 4, 5 and 6 I have illustrated a trough DA differing from the trough D of Figs. 1, 2 and 3 in the character of the stream dividing means associated therewith. In Figs. 4, 5 and 6, the two outlets E and F are connected to chambers EA and FA located beneath and extending transversely to the flow chamber in the trough DA. The chamber EA is open at its top to said flow channel through a port E¹⁵, the length of which may be varied by adjusting a plate like member E¹⁰ which forms a movable section of the floor of the trough. The plate E¹⁰ projects through a slot formed in the end wall of the chamber EA. The plate E¹⁰ may be adjusted in the direction of its length by means of a screw shaft E¹² working in a threaded opening in the end wall of the chamber EA and swivelled in ears E¹¹ formed at the under side of the plate E¹⁰, and provided at its outer end with a handwheel E¹⁴. The chamber FA is similar in construction to the chamber EA, and by

adjustment of the screw F^{12} , the plate F^{10} associated with the chamber FA is adjusted to vary the length of the port F^{15} through which the lime passes from the trough DA into the chamber FA . Advantageously and as shown, the ports E^{15} and F^{15} are located at the opposite sides of the trough, and one side portion of the liquid stream flowing down the trough DA passes through the port E^{15} to the outlet E , while a second side portion passes through the port F^{15} to the outlet F , and the central residue portion passes from the bottom of the trough back into the tank A . With either construction illustrated, an overflow connection I , shown in Figs. 4 and 5, may be employed to limit the maximum height of liquid level in the tank A .

While in accordance with the provisions 20 of the statutes I have illustrated and described the best forms of my invention now known to me, it will be apparent to those skilled in the art that changes may be made in the form of the apparatus disclosed with- 25 out departing from the spirit of my invention as set forth in the appended claims, and that certain features of the invention may sometimes be used with advantage without a corresponding use of other features of 30 the invention.

Having now described my invention, what I claim as new and desire to secure by Letters Patent, is:

1. Apparatus for delivering liquid at a 35 measured rate comprising a wheel revolving about a horizontal axis having a plurality of buckets spaced about the axis of the wheel, each of said buckets having a body portion curved about a horizontal axis 40 and having a lateral discharge opening through which the bucket discharges as it passes through an upper portion of its path of movement and having an end wall opening, the margin of which is curved about its 45 said axis so that the amount of liquid held in the bucket as the latter rises above a body of liquid into which the bucket is dipped by the rotation of the wheel is not varied by a change in level of said liquid body.

2. Apparatus for delivering liquid at a 50 measured rate comprising a disc revolving about a horizontal axis and having a plurality of buckets secured to one side of said disc, and spaced about the axis thereof, each 55 of said buckets having a body portion curved about a horizontal axis and having a lateral discharge opening through which the bucket discharges as it passes through an upper portion of its path of movement 60 and having an end wall opening, the margin of which is curved about its said axis so that the amount of liquid held in the bucket as the latter rises above a body of liquid into which the bucket is dipped by 65 the rotation of the wheel does not vary

with a change in level of said amount of liquid, the edge of said lateral opening over which the discharge takes place extending from the end of the bucket remote from said disc nearly but not quite to the latter. 70

3. Apparatus for the purpose described comprising a tank, an inclined delivery trough located above the liquid level in said tank, rotatable means for passing liquid at a measured rate from the lower portion of 75 the tank into the upper end of said trough, adjustable means for dividing the liquid passing downward through the trough into streams of regulated relative proportions, and means for separately withdrawing one 80 or more of said streams from the apparatus and for returning another of the streams to the liquid body held in said tank.

4. Apparatus of the character described 85 comprising a liquid holding tank, delivery trough located above the liquid level in said tank, means for passing liquid at a regulated rate from said tank to the inlet end of said trough, one or more vanes pivotally mounted in said trough and each adapted 90 to divide the liquid passing through the trough into separate streams, the relative proportions of which depend upon the adjustment of the vane.

5. Apparatus of the character described 95 comprising a liquid holding tank, a delivery trough, means for transferring liquid at a determined rate from said tank to the inlet end of said trough, said trough having a wide, flat bottom, means for dividing the 100 liquid flowing through the trough into streams, the relative magnitudes of which depend upon their relative widths, and means interposed between the last mentioned means and the inlet end of the trough for 105 uniformly distributing liquid over the trough bottom, said means comprising a spreader plate and means for holding the free edge of said spreader plate at a pre-determined distance above the bottom wall 110 of the trough.

6. Apparatus of the character described 115 comprising a liquid holding tank, a measuring wheel journaled in the tank structure to turn about an axis above the tank liquid level, said wheel being provided with buckets dipping into the liquid held in the tank as the wheel is rotated, a hood enclosing said measuring wheel, an inclined trough extending through the front wall of the hood into 120 position to receive liquid discharged by the buckets as the latter move through the upper portion of their path of movement, said trough having its body portion covered, means associated with the trough for dividing the liquid therein into a plurality of 125 separate streams, said means including parts external to the trough for varying the relative proportions of said streams.

7. Apparatus of the character described 130

comprising a liquid holding tank, an inclined delivery trough located above the liquid level in said tank, means for passing liquid at a regulated rate from said tank to the upper end of said trough, a plurality of liquid outlets adjacent the lower end of said trough, and means associated with said

trough for proportioning the amount of liquid passing down said trough to each of said outlets.

10

Signed at New York city, in the county of New York, and State of New York, this thirty-first day of August, A. D. 1927.

GEORGE A. N. WOODCOCK.
